UNITED STATES PATENT OFFICE.

MORIS MOOSE, OF CHICAGO, ILLINOIS.

CLASP AND TAG.

SPECIFICATION forming part of Letters Patent No. 416,796, dated December 10, 1889.

Application filed April 15, 1889. Serial No. 307,299. (No model.)

To all whom it may concern:

Be it known that I, MORIS MOOSE, a citizen of the United States, residing in the city of Chicago, county of Cook, and State of Illinois, 5 have invented certain new and useful Improvements in Clasps and Tags, of which the following is a specification.

My invention relates to improvements in clasps and tags; and it consists in certain peculiarieties of the construction and arrangement of the parts and in the novel manner of attaching the same, all of which will be hereinafter more fully set forth and specifically claimed.

15 The objects of my invention are to afford a reliable and effective yet simple and inexpensive means for marking articles—such as fabrics, hosiery, gloves, notions, &c.—which may be exposed for sale without the necessity 20 of pinning or sewing tickets on the articles so exposed for sale or for reference, as is the usual custom, and also enabling the marks to be easily and rapidly attached and detached, and that the same clasp may be repeatedly 25 used. I attain these objects by the mechanism illustrated in the drawings, and in order to enable others skilled in the art to which my invention pertains to make and use the same I will now proceed to describe it, referring to the accompanying drawings, in 30 which—

Figure 1 is a view of a piece of cloth with my clasp and tag attached. Fig. 2 is a view of my clasp before being bent. Fig. 3 is a 35 view of the tag; and Fig. 4 is a sectional end view through the cloth, clasp, and tag.

Similar letters refer to like parts throughout the different views of the drawings.

A represents a piece of cloth, fabric, or other 40 material to which my clasp B is or may be attached. The clasp B is made of suitable material, size, and form, but preferably of sheet metal and of the form shown in Fig. 2. Near each end of the clasp B, I puncture the material of which the clasp may be made with a pointed instrument and form therein a number of holes, depressions, or eyelets C C, which depressions or eyelets thus formed have the projections a a, which when pressed against 45 the cloth engage therewith, as seen in Fig. 4, and form a secure fastening. It is obvious

that I may indent the metal sufficiently to form the projections a a on the side opposite the indentation, or may pierce the holes entirely through the clasp, when the projections 55 will be formed as before, but will have rough or ragged edges which will engage with the cloth or material.

In the drawings I have shown the clasp-piece provided with two depressions or eyelets having projections a a, yet I do not wish to limit myself to this number, as I may use only one hole or may employ any number. After the clasp-piece is thus provided with depressions and projections it is slightly bent 60 and inserted in the slot E in the tag D, which tag is made of any suitable material, size, and form, and is provided at one end with a slot E, which I prefer to form with an enlargement F on the upper side of said slot 70 and near the center thereof to admit of the free passage of the projection a on the clasp B, and which prevents tearing or stopping in the slots by the projections on their course through. Of course I may form the tag with 75 a slot sufficiently wide to allow the projection to pass through without touching the edge of the slot; but I prefer to form it with the enlargement, as I am thereby enabled to use a much narrower slot and obtain a larger space 80 for marking purposes on the tag.

The operation of my device is simple and very effective. The clasp having the holes or depressions and projections is inserted in the slot E in the tag D, and is then bent and 85 closed on the cloth, with the projections on the inside. The marks are then placed on the tag, and the operation is complete. The clasp being made of very thin and flexible metal, it is easily bent and closed on the cloth by the fingers, and may be readily removed by prying 90 the ends apart and used again, as is apparent.

When it is desired to use my device for securing a tag to hard or almost solid substances, it will be necessary to use a thicker metal, 95 and after the bend is made in the clasp to drive the projections into the substance by a light blow from a hammer; but as the device is designed more especially for textiles and fabrics the use of the hammer will not be required.

Having thus fully described my invention,

what I claim as new, and desire to secure by Letters Patent, is—

As an improved article of manufacture, a clasp and tag consisting of the flexible clasp B, having the eyelets or depressions C C and projections a a, and the tag D, having the slot E, provided with enlargement F, substantially

as shown and described, and for the purpose set forth.

MORIS MOOSE.
